[57] CLAIM

The ornamental design for a “controller for game machine”, as shown and described.

DESCRIPTION

FIG. 1 is a front and right perspective view of a controller for a game machine showing a main embodiment;
FIG. 2 is a rear and left perspective view thereof;
FIG. 3 is a top plan view thereof;
FIG. 4 is a front elevational view thereof;
FIG. 5 is a rear elevational view thereof;
FIG. 6 is a bottom plan view thereof;
FIG. 7 is a right side view thereof;
FIG. 8 is a left side view thereof;
FIG. 9 is a front and right perspective view of a controller for a game machine showing a second embodiment;
FIG. 10 is a rear and left perspective view thereof;
FIG. 11 is a top plan view thereof;
FIG. 12 is a front elevational view thereof;
FIG. 13 is a rear elevational view thereof;
FIG. 14 is a bottom plan view thereof;
FIG. 15 is a right side view thereof; and,
FIG. 16 is a left side view thereof.
